Schweitzer & Conrad, Inc., Chicago, Ill., a cor-
poration of Delaware

Application May 8, 1933, Serial No. 669,955

82 Claims. (Cl. 200—120)

My invention relates to electrical circuit protective devices which are generally termed fuses. While the preferred embodiment herein disclosed is particularly applicable to use in high tension circuits, that is, circuits employing voltages suitable for transmission or distribution of electrical power, it is not intended to limit the invention to a particular use or voltage, the embodiments herein given being illustrative and not limiting.

The utility of devices of this general class is to interrupt current flow when the same becomes excessive. An electrical fuse is designed to depend for its action upon the heat evolved by current flow through a resistance. Heat is the safest criterion of excessive current flow because it is the ultimately destructive force released by such excessive current flow.

Fuses, as heretofore known and constructed, have had a twofold function, first, to respond in a particular way as, for example, by fusion, that is, melting, when the current flow rises above a predetermined value, and second, causing or permitting the substitution of an insulating medium for the conducting link upon the occurrence of the aforesaid response.

The melting of a fusible link, according to the general practice in devices of this character, proceeds to the vaporization of the metal of the link and the formation of an arc. Whereas a solid metallic conductor will increase in resistance as the temperature rises, and thereby tends to reduce the current flow, I find that as soon as the metal passes into the vapor form and the current is conducted therethrough in the nature of an arc, the resistance to current flow is greatly reduced. Why this is true I am not at present able to say, but assume that it is due to the greater cross-sectional area of the conductor, that is, the metallic vapor, and the relatively greater freedom of the ionized particles, or possibly greater freedom of the electrons to conduct current.

In known forms of high tension fuses it has been found desirable to deionize, or render inert, the metallic vapors, or to expel the same from the space between the terminals and finally to interpose, as soon as possible, a high value dielectric between the fuse terminals after the fuse blows.

The Schweitzer & Conrad high tension fuse is an example of a device now in general use. In the operation of this device, as in devices of a generally similar character, there are four stages of action brought about upon the occurrence of

current flow rising to excessive or destructive values.

1. Increase in resistance of the fuse link by excessive current flow, and a cumulative heating, resulting in fusion or melting of the metal. 5

2. Vaporization of the metal of the fuse and the formation of an arc.

3. Deionization of the arc by some action which interrupts the continuity of the current flow.

4. Interposition between the fuse terminals of a dielectric of a value high enough that restriking of the arc by a resurgent voltage will not occur.

In the Schweitzer & Conrad fuse, separation of the fuse terminals begins as soon as the fuse is melted in the first stage above mentioned.

With fuses operating according to the aforesaid mode of operation, the current flow that can occur during part or all of the stages of the existence of the arc is limited only by the capacity of the connected system and the reactance which remains in the circuit. As the connected capacity of the system is often very large, and the retained reactance small, the value of current flow through the arc occurring at the peak of the current wave sometimes rises to very high values.

There are also known the so-called powder filled cartridge fuses in which the interruption of current flow occurs without movement of the terminals and consequently without the fourth step above mentioned, namely, the positive interposition of a different medium between the terminals in substitution of the metallic link. 35 In commercial forms of powder-filled fuses there is the disadvantage that upon operation of the device no definite or marked change in the positions of the parts occurs, with resulting relative uncertainty as to the ability to avoid puncture, by the rise of voltage upon interruption of current flow. Such fuses, furthermore, have the disadvantage, upon high tension circuits, that the length of the fusible element must be so great that a serious problem is presented in finding room for the necessary electrostatic clearance. 40

If the fusible conductor is subject to permanent change in its carrying capacity without definite blowing, as when it is required to withstand current flow close to its rating or is subjected to momentary overloads then its rating may be changed without operation, and the functioning of the device becomes unreliable. This undesirable characteristic, while it constitutes a particular difficulty for powder filled fuses, will be 55

present more or less in any fuse unless special provisions are made to overcome it.

It is the chief object of the present invention to provide a current interrupting device involving, in the preferred form, a fusible link, which device shall provide means to avoid the high peaks of current flow in the system or bring them down to a value where the arc at the fusible link may easily be extinguished.

10 It is another object of the invention to provide a device which has two distinct cooperating elements, one a fusible link designed to have characteristics favorable to its function of providing and maintaining a definite rating to which 15 it responds, and the other a self-altering conductor designed to be insensitive to current flow of a value equal to the rating of the fuse but capable of reacting vigorously for currents substantially in excess of said fuse rating, to increase its 20 resistance rapidly and in a very pronounced degree.

I am aware that it is old to insert a fixed protective resistance in series with a transformer fuse or other fuse of relatively low capacity, such 25 as may be employed in instrument circuits. Such protective resistances limit the maximum current flow, first, by their resistance value at normal temperature, and second, by the increase 30 in resistance due to the heating under excessive current flow.

Such protective resistances, in order to be of appreciable effect, must be of such a high value that they definitely obstruct current flow of any 35 value. For instrument circuits and the like, the current flow is so small in value that the energy 40 loss is not important, but in power circuits the loss in energy would be so great as to make the problem of dissipation of the resultant heat serious, and the loss of energy would also become serious. Hence, the employment of a fixed current limiting resistance in series with a power carrying fuse or fusible device has not been practiced.

It is one of the chief objects of the present invention to provide a protective device in which an automatic current limiting resistance of the self-altering type is employed for limiting the maximum current flow, for use both in low current fuses such as employed for instrument 50 work, and in fuses of larger rating, such as are employed for power current transmitting purposes. The energy release in the system is thereby controlled and is kept low.

I have conceived the possibility of providing 55 a circuit protective device in which a fuse element with a fusible link is employed in correlation with a resistance element having an automatically increasable resistor, normally of low value, but adapted, when the current flow 60 through the device increases at a rate which presages a high peak value, of permanently increasing its value so greatly as to limit the current flow to a value which permits the fuse element to disconnect the circuit. The increase of 65 the included resistance may be so great as to reduce the current flow to zero. However, in the preferred embodiment of my invention, the fuse element has a movable member performing the function of interposing a definite gap in the circuit, under any condition of operation of the device.

The device of my invention has selective modes of operation for different conditions of current increase therethrough, as I shall here briefly 75 explain. A fuse such as the Schweitzer & Con-

rad fuse has a definite action when the current flow increases to a value which causes the fuse to melt. When the fuse melts, the retractile spring takes control and separates the fuse terminals and brings the arc extinguishing medium 5 into play.

The oxidizable or otherwise self-altering resistance of the present invention acts differently. It is not intended to establish an arc under any condition. Its initial resistance in the present device is relatively low. It is not designed to act until the current flow reaches a value substantially in excess of that at which the fuse blows.

If the rate of current increase through the 15 device is relatively low, the current flow may be interrupted at the fuse link with little, if any, permanent change in the resistor.

If the fault current is low, the device may operate by yielding of the fusible link and extinguishment of the arc which ensues at this point, without calling the automatic resistance into play. This action may occur with or without removal of the cap by the action of extinguishing the arc according to the usual operation of 25 fuses.

The resistor, in oxidizing or otherwise altering itself, acts quantitatively and cumulatively. If the rate of increase of current flow through the device is high, so that it passes far beyond the 30 rated value of the fuse, the action of the fuse element will be relatively ineffective as compared with the action of the self-altering resistor, which then takes control to limit the current flow to a value where the arc cannot be sustained and is extinguished and the movable terminal of the fuse can effect the disconnection or interposition of a gap of so great a value that restoring of the voltage will not reestablish the 35 arc.

Thus, for low rates of current rise, the fuse 40 may retain control, but on high rates of current rise the resistor alters its own value and takes control.

Where, as in one embodiment, the fuse element and resistance element are initially connected in the circuit in series, the movable terminal or terminals of the fuse serve to increase the length of the arc, inject an arc extinguishing medium, and to interpose the final disconnecting gap. Where, as in another embodiment, the fuse element and resistance element are disposed in parallel, the movable terminals have, in addition to the above function, the function of causing a shift in the current flow from the 55 path including the fuse element to the path including the resistance.

In another embodiment, where the resistor is normally out of circuit, the movable terminal or terminals have the additional function of bringing 60 the resistor into circuit.

In all the embodiments herein disclosed it is intended that if the fault current be low, the device shall clear the circuit at the fusible element. In that case the fusible element yields, the arc 65 is formed, and is extinguished, with or without blowing of the cap, but without calling the automatic self-altering resistance into action.

This is possible because the fusible element or fuse is designed and constructed to melt at its 70 rating, which is also the rating of the device. Now, although the fusible section is designed to melt when its rated blowing current is reached, the current may continue to increase to an immensely greater value during arcing at the gap. 75

If this should occur, it would put an enormous duty upon the fuse which would create an excessive disturbance and a possible failure. But the self-altering resistor, which is so designed or connected as not in anywise to be affected by the mere rated current of the fuse, comes into operation either because it is in permanent series connection, or because it is switched into the circuit either in series or parallel in a decisive manner 5 when the current rises beyond the value at which the fuse is intended to blow, and promptly alters its resistance, thereby relieving the fuse of excessive duty. The reason that the self-altering resistor, when permanently connected in series 10 in the circuit, does not act at the current value which melts the fuse is that the resistor is designed to carry a current which will melt the fuse without heating up to a temperature which will initiate the chemical reaction. But as the 15 current goes to a value which heats the resistor to a temperature at which the reaction begins, the resistor alters its conductivity. The more it reduces its conductivity the higher its resistance rises, and the hotter it tends to become. The 20 action thus is cumulatively accelerated. In those cases when the resistor is normally not in the circuit, but is switched into the circuit either in parallel or in series with the arc or a part of the arc, it is saved from deterioration by the fact 25 that it is not subjected to current flow until the fuse melts.

The device thus includes the combination of fuse element and resistance element connected either in series or parallel arrangement, in either 30 a permanent manner or in a manner to be automatically switched into the circuit upon the necessity for the same arising.

The fuse element, when it operates, introduces a permanent gap in the circuit, and the resistance element, when it operates, introduces a permanent increase in the resistance of the device.

The current limiting resistance element which I employ in the preferred form of my invention has the characteristic of increasing cumulatively its own resistance, not merely by the thermal coefficient of resistance which is a property of the metal employed, but by a chemical union with a reagent which is liberated by the temperature attained by the element. This reaction, 45 which produces a permanent change, reduces the element to a non-conductive form, preferably without arriving at the stage of forming free metal vapor as a part of the current carrying path.

50 With these two dissimilar types of current responsive devices it is possible to secure current interruption within a device of relatively small dimensions and without the necessity for venting vapors or gases to atmosphere.

60 In fuses of the type which permit the fusion of the link to proceed to vaporization of the metal and the establishment of an arc therethrough without control of the resistance of the circuit, there is always the possibility of the release of 65 large amounts of energy in the form of heat, with resultant excessive fluid pressure. It is known to employ a deionizing agent which can be conducted into a separate chamber and to some extent hold down the pressure by condensing 70 the vapors and gases. Nevertheless, the tendency to evolve great pressure is present where the resistance of the circuit is uncontrolled. If the resistance of the circuit can be adequately controlled before the rush of current reaches too 75 high a value, then the violence of the arc, with

resultant fluid pressure, can likewise be controlled, and special condensing chambers or undesirable venting of gases and vapors to atmosphere may be avoided.

The positive separation of the terminals of a 5 device of this character, acting to interpose a definite dielectric medium, is highly desirable, particularly where, as in the preferred form of the present invention, a glass container is employed which gives the possibility of visual inspection to determine the condition of the device. Such visual inspection of a gap in the circuit of the device is highly desirable.

There are numerous improvements in detail provided by the present invention. These will 10 be apparent from the following specification and drawings.

Now in order to acquaint those skilled in the art with the manner of constructing and operating a device embodying my invention I shall 15 describe, in connection with the accompanying drawings, a specific embodiment of the invention, and shall state its mode of operation.

In the drawings:

Figure 1 is a diagram illustrating the connection of the fuse, with the fusible element, the operating spring, and the cooperating resistance element in series;

Figure 2 is a similar diagram illustrating the connections of the form of device in which the 30 resistor element is switched in upon blowing of the fusible element;

Figure 3 is a similar diagram showing the fusible element and the resistance element connected 35 or switched in parallel;

Figure 4, shown in two parts, is a vertical longitudinal section through an embodiment of my invention. Part 1 shows the upper portion of the fuse, in section, and part 2 shows the lower portion of the fuse, in section;

Figure 5 is a diagram illustrative of the mode 40 of operation of the device shown in Figures 1 and 4;

Figure 6, in two parts, is a vertical longitudinal section through a modified form of my invention, part 1 showing the upper portion of the fuse, in section, and part 2 showing the lower portion of the fuse, in section;

Figure 7 is a view similar to Figure 6, part 2, showing a modified arrangement of the lower 50 portion of the device of either Figure 1 or Figure 6;

Figure 8 is a cross-section of the device shown in Fig. 7, taken on the line 8—8 of Figure 7;

Figure 9, two parts, is a longitudinal vertical 55 section through another form of fuse embodying the connection shown in Figure 2. Part 1 shows the upper part of the device, in section, and part 2 shows the lower part of the device, in section;

Figure 10 is a vertical longitudinal section through a modified form of my invention, embodying the connection shown in Figure 3; and

Figure 11 is a sectional view of a modification 60 of the fuse-containing tube, taken on line 11—11 of Figure 9, part 1.

Referring now to the embodiment shown in Figures 1 and 4, I provide a completely enclosed element employing the enclosing sleeve 1 of glass. Other suitable insulating material may be employed, but glass has the desirable characteristic of transparency, to indicate to the observer the condition of the device, that is, whether it has opened the circuit or not. Upon the upper end 65 of the glass sleeve 1 there is mounted the ferrule 70

2 which forms an external terminal suitable for mounting in a spring clip or the like, for connection of the device in an external circuit. Similarly, the lower end of the sleeve 1 has a metal 5 ferrule, closed at its lower end, this ferrule 3 being in the shape of a cap. The ferrules 2 and 3 are secured upon the ends of the glass or other insulating sleeve 1 by a suitable sealing alloy 10 or compound 4, making a tight joint, mechanically and pneumatically. Between the upper ferrule 2 and the lower ferrule 3 there are connected two dissimilar current responsive elements, namely, the fuse element 5 and the resistance element 6. The fuse element 5 comprises a silver wire 7 15 which serves to conduct normal flow of current and to fuse upon the flow of excess current. A high tensile strength member 8, which is preferably of a nickel-chromium-alloy such as "Ni-chrome" or "Chromel", sustains the pull exerted 20 by the retracting spring 9. Its function is largely mechanical, as will be apparent later. The resistance element 6 comprises a tungsten wire 10 disposed in loose coils and surrounded by a compound which, upon being heated, releases a chemical 25 reagent that combines with the substance of the wire 10 and causes it to become substantially or completely non-conductive. The compound 12 may be calcium carbonate, in the form of marble dust or other suitable or equivalent material for 30 performing the function which it is the purpose of the marble dust to perform. The silver wire 7, which is the fusible element proper, is substantially free of any deterioration due to heating to approximately its melting point. In other 35 words, this element is designed to remain intact until current flow through it indicates such a release of energy in the connected circuit that the entire device should operate to interrupt current flow. The resistance wire 10, on the contrary, 40 would be subjected to possible deterioration by a transient or temporary value of current flow in excess of normal, hence its purpose is to remain unchanged until the rate of energy release, i. e., heating, indicates a low resistance fault in the 45 circuit. The fusible wire 7 determines definitely when the device shall operate, by vaporizing and forming an arc. The resistance wire 10 has the property of increasing its resistance by current flow and, in addition, upon high rates of 50 energy release, of evolving carbon dioxide or oxygen from the calcium carbonate and combining with the oxygen thereof to produce tungsten oxide, which is substantially non-conductive, and thereby permanently increasing its resistance to 55 a point where it is substantially non-conductive in character, without the formation of an arc. Other compounds may be formed, but if so they are substantially non-conductive. The silver wire 7 tends, of course, to increase its resistance to 60 current flow so long as it is increasing in temperature without melting, but this is of no appreciable or effective value. The silver wire 7 will melt at a temperature far below the melting point of the tungsten wire 10, although the current is 65 flowing through the two wires in series. The effect of a high increase in current flow on the resistance wire 10 is to cause it to increase in temperature up to the point of releasing carbon dioxide or oxygen from the compound 12 and 70 itself becoming chemically active. The wire attains such a temperature as readily to combine with some of the constituents of the marble dust, to convert itself to a non-conductive oxide or other compound. The heating up and the consequent chemical reaction occur normally within a half 75

cycle or less. As a result, the device is able to interrupt current flow without allowing the liberation of much energy in the system. That is to say, the current flow is interrupted promptly, and without allowing the value of current flow to reach peak values such as would occur without the limiting effect of the wire 10.

In Figure 5 I have indicated the comparative effects of the present fuse and previously known forms of fuses for interrupting current flow upon the occurrence of a substantially dead short-circuit. In Figure 5 the sine wave graph A indicates the impressed voltage upon the circuit protected by the device. The sine wave graph B indicates the voltage across the terminals of the 15 device. The line C indicates the current flow through the device of Figs. 1 and 4. The horizontal portion of the line C indicates zero current. The light vertical lines D and E indicate the period of time during which short-circuit current was flowing. It is to be observed that the short-circuit was applied as the potential wave A passed through zero. This is the most severe condition. The peak of current flow indicated at F reached approximately 600 amperes and the interruption occurred in an exceedingly short space of time, that is, less than half of a half-cycle. As determined by the oscillograph, the circuit was interrupted in a period of time 25 represented as 0.0026 second. 30

In previous forms of fuses in which the interruption has depended entirely upon extinguishment of current flow at the fusible conductor, such as the silver wire 7, the peak of current flow reaches a value indicated by the dotted line G, 35 attaining a value of approximately 11,000 amperes and extending over a period of time approximately .014 second.

In such prior fuses extinction of the arc is not accomplished until the current wave passes 40 through zero value. These zero values tend to occur at definitely timed intervals, i. e., twice per cycle. Hence, in such prior forms of circuit interrupters, the current has the opportunity to rise to a high peak, with the ability to release 45 relatively great amounts of energy in the system. This time may be further extended by the shift in phase which may occur. Hence, a low resistance fault may cause serious damage to the connected apparatus, conductors, etc. 50

Now I shall describe in detail the structure of the device shown in Figures 1 and 4, which brings about the operation above described.

The silver fuse wire 7 is connected between a stationary terminal stud 13 and a movable terminal stud 14. These terminal studs are slotted, the ends of the wire 7 laid thereinto and the edges of the slots battered over to embrace the corresponding parts of the fuse wire. The strain wire 8 is anchored in bores in terminals 13 and 14, the ends of the strain wire being formed into loops with transverse pins extending through the same. The mounting of the strain wire 8 in the terminal studs 13 and 14 is disclosed in the co-pending application of N. J. Conrad, Serial No. 470,416, filed July 24, 1930, and forms no feature of the present invention. Suffice it to say that the mounting gives the strain wire a suitable limited degree of universal motion. 55

The fuse wire 7 is coiled about the strain wire 8 and a body of cork 15, with an opening through the center of the same, embraces the terminals 13 and 14 and encloses the fuse wire 7 and strain wire 8. The stud 13 is mounted upon a suitable spring spider 16 which is seated in a counterbore 60

65

70

75

17 and upon a shoulder 18 in the upper end of the ferrule 2. The upper end of the ferrule is closed by a releasable cap 19 which is held in place by a suitable cement, to give a definite holding value to retain pressure within the device up to a pre-determined value. The container formed by the sleeve 1 and ferrules 2 and 3 is substantially filled with an arc extinguishing liquid 20 which may be a halogen derivative of a hydrocarbon. Any suitable arc extinguishing liquid or medium may be employed. The level of the liquid stands normally, when at room temperature, approximately at the line Y—Y. If the cork is pulled down, in operation, the level may rise to X—X. The movable terminal stud 14 carries the liquid director 22 for projecting a stream of the liquid 20 upon the tip 14 as the same descends after blowing of the fuse 5. The terminal stud 14 is secured by the screw 23 to the upper end of a tension spring 9 through the medium of a clamp 25. The lower end of the spring 9 is secured by a similar clamping plate 26 and screw 27 to a stud 28 which is threaded into a terminal socket formed in the metal head 29 forming the upper part of the enclosure for the resistance wire 10.

The enclosure for the resistance wire 10 and its filling 12 comprises the "Bakelized" fiber sleeve 30 which has a longitudinal groove 32 extending the full length thereof and two circumferential grooves, namely, 33 at the upper end and 34 at the lower end. The resistance wire 10 is formed in a helical coil with the ends thereof extending axially and secured in head members 35—35 of generally cylindrical form with extending threaded studs 36, as shown at the lower end. These studs are threaded into head members 37 and 38. Each of the terminal members 35 has a radially extending pin 39 acting as a key sliding in the slot or keyway 32 to prevent rotation. The heads 37 and 38 are guided in the ends of the sleeve 30 and at their inner ends are reduced in diameter to provide, in effect, a groove for receiving a split wire ring 40—40 preventing end-wise movement.

The head members 37—38 have conical flanges overhanging the ends of the sleeve 30 to provide a substantially tight closure. The heads 37 and 38 are threaded down upon the studs 36 and the conical flanges act like poppet valves to close off the ends of the sleeve 30. As a result, the generation of gas pressure within the sleeve 30 may occur without immediate transmission of the pressure to the inside of the glass sleeve 1.

The lower head 38 has an extending threaded stud 42 which is threaded into a boss 43 on the inside of the cap 3.

The operation of the device is as follows: Assuming that current flow in excess of the rated capacity of the device occurs, if this excess is but temporary the silver fuse wire 1 will carry the same without fusion and without deterioration by corrosion or scaling or the like. Practically all of the current flows through the wire 1 and very little through the strain wire 8, since it is of high resistance. If, however, the rise in current is sharp and pronounced, as in the case of a short circuit, the temperature of the wire 1 rises rapidly. If the current rises at a rate which corresponds to a low resistance fault in the system the fuse wire 1 rapidly reaches the vaporizing point, with immediate fusing of the wire 8 and the formation of an arc between the terminals 13 and 14, and a decrease in the resistance between the said terminals 13 and 14. The same current flow which extends through the arc extends in

series through the tungsten wire 10 and the current flow through the fuse and the ensuing arc causes heating of the tungsten wire 10. It is in contact with the marble dust 12, and since a relatively low temperature only is required to calcine the marble dust it begins to give off carbon dioxide at a temperature below the melting point of the tungsten wire. The tungsten wire continues to rise in temperature, reaching incandescence without losing its character as a solid. At incandescence it is actively attacked by the oxygen released from the marble dust, being converted into tungsten oxide. This compound is substantially non-conductive. Other compounds may be formed. I am not able to say positively the exact reaction that occurs. It may be that the reactions are more complex than above indicated, and other products may be formed. They are, however, substantially non-conductive, so far as my tests indicate.

As soon as the fuse 5 has blown, the spring 9 is free to retract the terminal 14. However, the action of the tungsten wire 10 in heating up and oxidizing is so rapid that it will be converted into a non-conductor before the terminal 14 has moved more than approximately $\frac{1}{4}$ inch. However, after being once released, the terminal 14 continues to move with an accelerated motion and inasmuch as the resistance of the wire 10 begins to increase with great rapidity as soon as it has reached incandescence, the arc which might be maintained between the terminals 13 and 14 is extinguished quickly and without violence. As the terminal 14 recedes it is drawn under the liquid 20, which liquid, being of a high dielectric strength, interposes itself in the gap between the terminals 13 and 14 and prevents striking back of the arc, interposing a definite dielectric, and giving a visible indication of the fact that the fuse has opened the circuit.

The two elements, namely, the fuse 5 and the resistance 6, are of distinctly different character and each supplements the action of the other. The fuse element 5 determines when the device shall positively operate, whereas the element 6 will act quantitatively when the value of current flow initiating its operation occurs. The element 5 operates to interpose a non-conductor by first forming a gaseous conductor, that is, an arc, but the arc is kept under control both by the extinguishing mechanisms, namely, the cork 15, liquid director 22, and liquid dielectric 20, as well as by the resistance member 6. The two elements 5 and 6 are disposed at opposite ends of the casing so that each is out of the other's influence to as great an extent as possible. That is to say, the arc which may occur at the element 5 should be kept away from the resistance 6 and likewise it is desirable that any chemical action which might occur in connection with the element 6 should be kept away from the element 5. The carbon dioxide gas which is generated in the specific combination of elements here disclosed has no adverse effect, so far as I can determine upon the silver fuse wire 1 nor the alloy strain wire 8. However, the ingredients may be varied, and in that event the reagent which may be employed in connection with the element 6 might be detrimental to the element 5.

The embodiment shown in Figure 4 is particularly applicable for small values of normal current flow, that is, the rating of the fuse is not in excess of 5 amperes. In such case the resistance of the tungsten wire 10 is of the order of 0.2 ohms.

The marble dust, or calcium carbonate, is in-

ert at relatively low temperatures and it must be heated by the tungsten wire before it will release any reagent. The release of carbon dioxide by the heat of the tungsten wire is accomplished without the marble dust passing through the vapor stage or without boiling off any appreciable amount of the liquid which may find its way into the marble dust. Exclusion of the liquid dielectric from the inside of the sleeve 30 is desirable. The tungsten must be heated to a value of the order of 1400° C. before it becomes active in combination with the carbon dioxide or the oxygen released by the marble dust. In reaching this temperature it increases its resistance of the order of seven to ten times. Where other reagents are used, or where a different composition of the wire with the same or a different reagent is used, the temperatures at which operation occurs may be different.

While I prefer to dispose the fuse 5 at the opposite end of the casing from the resistance 6, and design each to perform its function out of the influence of the other, I do not wish to limit the arrangement to such separation, for the fusible element may be made a direct continuation of the infusible resistance conductor 10, or disposed in close proximity to the same. The thing which is not desired is any interference between the action of the arc and the action of the conductor 10.

The specific embodiments of the element 6, which contains the oxidizable or chemically combinable conductor 10, may be varied, as may the fuse member 5, which includes the vaporizable conductor 7.

In the embodiment of Figure 6 the fuse element 5a, as well as the resistance element 6a, exhibits a modification in structure and individual mode of operation, but the cooperating action is as above described. The fuse element and the resistance element, 5a and 6a, respectively, are continuously connected in series in this embodiment.

The fuse 5a is constructed substantially as disclosed in the copending Patent No. 1,907,581, granted May 9, 1933. The fusible element is a nickel-chromium-alloy wire of small diameter, indicated at Figure 6, part 1, by the reference numeral 50. The upper end of the fuse wire is connected to a terminal block 52, this terminal block having a threaded stud 53 extending upwardly through the spring spider member 54. The spring spider member comprises a plate having a hole through the center for receiving the stud 53 and has the spring fingers formed by slotting the flange as indicated at 55, these spring fingers engaging in the counterbore 17 and resting endwise upon the ledge or shoulder 18. A clamping nut 56 holds the block 52 against the bottom of the spider 54. At its lower end the silver fuse wire 50 is connected to a lever 57 pivoted at 58 between two plates of insulation 59. The free end of the lever 57 is connected to the fuse wire 50. A series of levers 60, 60a and 60b are pivoted alternately upon opposite sides of the center line and rest upon each other, the lower lever 60b resting upon the lever 57 to which the fuse wire 50 is secured. A loop of high tensile strength wire or of sheet metal of adequate current carrying capacity is connected between the uppermost lever 60 and the movable terminal 63. This loop 62 is made in the shape of an open link having an eye at each end. At the upper end the link rests upon the lever 60 and at its lower end the link is inserted in an axial opening in the movable terminal 63 and held in place by a cross-pin 54. The plates of

insulation 58 are slotted to receive the link 62. The link 62 is not intended to be fusible. A barrier member or transverse plate 65 is threaded internally in the upper end of the ferrule 2 and it has a counterbore and shoulder 66 to receive the upper end of the tube 67 defining the arcing chamber. This tube 67 has a head or enlargement 68 resting in the counterbore of the barrier plate 65. The tube or sleeve of insulation 67 is held in place by a plurality of washers 69-69 overhanging the upper edge of the head 68 and secured in place by the pins 70, which are pressed into the barrier plate or head member 65. Instead of a series of washers a single continuous ring or equivalent arrangement for holding the upper end of the arcing tube 67 in place may be employed.

The movable terminal 63 carries the liquid director 22, a series of pins 72 extending radially out from the movable terminal 63 and engaging in a groove in the liquid director 22. The liquid director 22 and the movable terminal 63 are telescoped with the lower end of the arcing chamber 67. The sleeve 1 is filled with arc extinguishing liquid which extends to approximately the level Z-Z of Figure 6, part 1. The lower end of the movable terminal 63 is connected to the head 13 by a threaded stud 14. The tension spring 9 is connected to the spring head 13. The lower end of the spring head 13 has a socket 11 for receiving the flexible conductor 24. A similar spring head 15, having the socket 16 for the flexible conductor 24, is disposed at the opposite end of the spring. The head 15 is anchored to a terminal member 11 forming the upper end of the resistance member 6a, as by means of a suitable stud on the head member 15 and a socket in the terminal member 11.

The unit 6a comprises the upper head member 11 and the lower head member 15, these head members having internally threaded sockets 19-19 and centrally disposed tapered studs 80-80, substantially alike in construction. The threaded sockets 19 receive the threaded ends of the sleeve 82, which is made of "Bakelized" fiber or like insulating material. The central projections 80, which are tapered at a relatively small angle, fit closely in the tapered sockets formed in the outer ends of the sleeve of insulation 82 to form substantially fluid-tight joints. A suitable sealing material may be employed in connection with the threads of the sockets 19 and the fit of the tapered plugs 80, so as to seal off the inside of the unit 6a from the outside thereof by fluid-tight seal. The projections 80-80 have central axial recesses in which are disposed springs 83-83 placed under compression to secure definite contact between the head members 11 and 15 and the corresponding terminal members of the wire 10. The terminal members of wire 10 comprise sheet metal plates or discs 84-84 set in grooves 85-85. The compression of the springs 83-83 and the tension of the resistance wire 10 hold these discs or plates 84-84 expanded into the grooves 85-85 and thereby hold the same definitely in place. The interior of the sleeve 82 is filled with a filling of marble dust 12, or the like, and the wire 10 is made of tungsten or the like. The desideratum is to have a wire of very high melting point which is capable, when it has reached a high temperature, of releasing a reagent from the compound 12, which reagent will combine with the substance of the wire 10 to produce an insulating, or substantially 75

non-conducting compound of the substance of the wire 10.

The fuse shown in Figure 6 is designed for very low current rating and it is for this reason 5 that the fusible wire 50 is given the mechanical advantage over the spring 9. In point of overall operation the operation of the device shown 10 in Figure 6 is like that described in connection with the device of Figure 4. Specifically, the 15 operation of the fuse element 5a corresponds to the mechanism therein disclosed. As soon as the current through the device has attained a value which softens or melts the fuse wire 50, the lowermost lever 57 is released, and progressively 20 these concatenated levers releases the link 62, whereupon the spring 9 moves the terminal 63, with its connected link 62, downwardly. The arc which follows the rupturing of the fuse 50 is confined radially within the sleeve or arcing chamber 67, and the descent of the terminal 25 63 with the liquid director 22 projects liquid into the arcing chamber, tending to drive out the metal vapors through the upper end of the sleeve 67, to extinguish the arc. However, the cooperation 30 between the fuse 5a and the resistance wire 10 is as heretofore described. The wire 10 increases its resistance by heating. When a temperature has been reached which releases the required chemical reagent from the compound 12, such reagent is freed and is in position and condition to attack the material of the wire 10 as soon as it reaches the ignition temperature or the temperature at which it is 35 chemically active. The wire 10 then burns to a non-conducting oxide with great rapidity. In fact, the action is accelerated.

I am not able to say that the chemical reaction is altogether an oxidation of the tungsten. There may be other compounds formed, but the 40 reaction is effective to produce the result desired, and whether the tungsten combines with the calcium in more or less degree, or whether the reaction is entirely an oxidation, I have not as yet been able to ascertain. I believe that the significant and useful reaction is oxidation.

The unit 6a is sealed air-tight by the application 45 of a compound which is not dissolved in the arc extinguishing liquid with which the device is filled. The arc extinguishing liquid continues 50 into the lowermost part of the device in Figure 6 and completely surrounds the unit 6a.

In Figures 7 and 8 I have shown a modified 55 embodiment of the resistance unit designated 6b. The upper end of the device, including the fuse, is identical with Figure 6, part 1, and therefore need not be described.

In the construction shown in Figures 7 and 8 the resistance unit 6b is provided with a vent to 60 atmosphere. The upper terminal and ferrule member 87 is mounted upon the upper end of the glass sleeve 89 by means of the sealing alloy 4 which is preferably the same alloy employed 65 in sealing the upper and lower ferrules 2 and 3 upon the main glass sleeve 1.

The lower ferrule member 88 of the unit 6b 70 is likewise sealed upon the lower end of the glass sleeve 89. The upper member 87 is imperforate, having a socket externally at its upper 75 end for receiving the stud of the lower spring head 15, and is provided internally with a socket 90 for receiving the stud 92. This stud 92 is preferably in the form of a screw provided with a suitable screwdriver slot and having secured in its head the upper end of the resistance wire

10. The lower head and ferrule member 88 is 75 perforated and has a counterbore 93 in which there is disposed a curved crossbar 94 forming a terminal for the lower end of the resistance wire 10. Said resistance wire has a hook-like 5 extremity hooked over a crosspin 95 lying in a slot 96 in the bar 94.

The lower ferrule member 3 on the main glass sleeve 1 is bored out to provide a cylindrical guiding surface 97, which engages a corresponding cylindrical surface on the sleeve member 88 of the unit 6b. The main ferrule member 3 is threaded and counterbored to provide the surface 99 against which a corresponding enlargement of the sleeve member 88 of the unit 15 6b engages and between the shoulders formed by the counterbore and the enlargement there is a space 98 which is filled with a suitable sealing compound of a character which is not attacked by the liquid arc extinguishing material 20 which 20 fills the main sleeve 1. The outer sleeve member 3 has a further counterbore 108 and the inner sleeve member 88 has a flange or head 102 for providing a positive endwise engagement 25 between the ferrules 3 and 88. Adjacent the flange or enlargement 102 there is a groove 103 formed in the sleeve or ferrule member 88 and this groove is filled with a sealing compound which is unaffected by moisture. Two different sealing compounds are used, the outer one to 30 seal against moisture and the inner one to seal against the arc extinguishing liquid, since each may thus be selected best to perform its function. The flange or head 102 of the inner sleeve 88 is clamped in place by a screw plug 104 which is threaded into the open end of the ferrule 3 and clamps the flange 102. At the same time, a central stud 106 presses against the center of the crossbar or terminal member 94, holding it definitely in place in its recess or counterbore 93. An annular disc or washer 107 lies in the annular recess formed in the plug member 104, this disc or washer 107 being porous, and consisting preferably of a soft fibrous material such as asbestos. Waterproof paper sheets 108 45 are disposed on opposite sides of the asbestos washer 107, or, if desired, the lower paper sealing washer alone may be employed, the upper one being omitted. Vent openings 105 extend through the plug member 104, these vent openings permitting the escape of gas pressure from within the chamber in which the resistance wire and its filling material 12 are contained.

The inner walls of the glass sleeve 89 may be 50 lined with a material which will insulate the glass sleeve from the intense heat of the wire 10. To this end a lining 109 of plaster of Paris may be cast in place.

The operation of the unit shown in 6b is substantially identical with that of the resistance 60 units 6 and 6a heretofore described. However, the interior of the unit 6b can vent to atmosphere through the asbestos washer 107 by rupturing the paper sealing disc or discs 108 and passing through the vent openings 105. This does not 65 permit escape of the arc extinguishing liquid since the unit 6b, although surrounded by the arc extinguishing liquid, has its interior completely sealed off from said liquid.

The type of device above described has a number 70 of distinct advantages. It is old to employ a fixed resistor in series with a fuse, particularly fuses of low current carrying capacity, but where a fixed resistor is employed the resistance must be of a relatively high value to be of any worth. 75

In a fuse for 15 k. v. circuits, such as the devices above described, the short circuit current may rise to 10,000 to 15,000 amperes during the first half-cycle if the fault is of low resistance. For 5 a fixed resistor to have a sufficient limiting effect to prevent blowing of the cap off of the fuse it must be of the order of from 20 to 480 ohms, depending upon the voltage of the system. However, such a large amount of resistance is too 10 bulky to be incorporated in a fuse. By the provision of a resistor which automatically increases its resistance with current flow, there is a highly desirable action. The I^2R loss may be made very 15 low for normal current flow, in view of the fact that the resistor is of low order, for example, 2/10 of an ohm. The choking effect of the automatic resistor being dependent upon current flow therethrough, permits the resistor not only to put a limit upon the current flow which passes through 20 the device but actually assists in extinguishing such current flow and allows the disconnection of the circuit within the device to occur without violence. Such a device as I have above described 25 may, therefore, be employed in limited installation space and without danger of causing faults by its operation.

If the device is subjected to very low fault current the fuse element operates without the current having increased to such a value as to bring 30 the automatic resistance into action. For example, in the device shown in Figure 6, the normal RMS load current may be 1/10 ampere. The instantaneous value of current on low fault current conditions starts out to reach a peak of from 1 35 to 2 amperes, such as occurs in the primary circuit of a current transformer when the secondary terminals are short circuited. The fuse element such as the silver wire 58 melts, but the tungsten wire 10 is not heated to any appreciably effective 40 temperature and it does not come into action to reduce its conductivity. Interruption occurs at the fuse element by liquid quenching and deionization of the arc in the normal manner without developing any violence in pressure which would 45 require the cap 19 to be blown off.

Assume, however, that there is a low resistance fault. Then, although the normal RMS load current may be only 1/10 ampere, the instantaneous value of current starts out to reach a peak of 50 say 10,000 amperes, such as occurs in the primary circuit of a current transformer in case the primary terminals are short circuited. Immediately the fuse element melts, and the arc starts 55 at the fuse terminals. The rapidly increasing current passes through the arc and through the tungsten wire. In fact, the tungsten wire begins to increase in resistance by its automatic action before the fuse element is melted. The ohmic resistance increase of the tungsten wire is negligible 60 in the total circuit resistance and is not effective in holding down the current. Arcing at the fuse element increases rapidly and heating of the tungsten as rapidly results in oxidizing temperature for the tungsten with the evolution of oxygen 65 from the calcium carbonate. The chemical combination between the oxygen and the tungsten rapidly reduces the cross-sectional area of the tungsten, thereby greatly accelerating the increase in resistance. This proceeds with great 70 rapidity, to the order of 10 megohms, that is, substantially an insulator, and halts the rise of current in its own path which has been proceeding towards a flow of 10,000 amperes. The increase of resistance is so rapid as to halt the increase of current flow and immediately reduce it

to zero after it has reached an instantaneous value of not greater than 500 to 600 amperes. The actual interruption of current flow may occur either at the fuse 58 or within the tungsten wire resistance. During the rapid reduction in current 5 caused by the rapid increase in the series resistance element, the arc becomes unable to maintain itself and is quenched at the fuse terminals. It may be that the tungsten wire in approaching a substantially non-conductive condition, breaks 10 into a series of fine arcs throughout its length, which arcs cannot be maintained by the available voltage and the arcs then become snuffed out, but it is to be observed that if any appreciable arcing should occur through the resistance element the 15 resistance of the path would immediately be reduced and the duty of interruption would then fall upon the fuse element. Upon interruption of the current flow, the resistance, which has been converted into substantially a non-conductor, 20 and the interposed fuse liquid in the fuse element, prevent reestablishment of current flow through the device. The fuse element with the retractile terminal performs, in any event, the important duty of disconnecting the circuit, that 25 is, moving the terminals of the circuit so far from each other, and interposing a dielectric, that the arc cannot be reestablished by puncture.

Due to the fact that the automatic resistance is dependent for its action upon current flow, the 30 increase in resistance rapidly overtakes the increase in current flow and halts the release of energy in the fuse. The result is that the device operates with unusually low energy release. When the parts are properly proportioned the 35 vent cap will not be blown off and no external disturbance is created. The disconnection or operation of the fuse may readily be observed through the glass sleeve 1.

In the device shown in Figure 9, parts 1 and 2, 40 I have illustrated an embodiment in which the fuse and the resistance are connected in series when the valve raises. Normally, the valve contact short circuits the resistance. In this construction the glass sleeve 1 has the ferrule 2 at 45 its upper end and the cap 3 at its lower end cemented by suitable sealing alloy 4 to retain a suitable charge of dielectric arc extinguishing liquid 20. The spring 9 has a head 73 at its upper end coupling the same through a coupling 74 to the rod-like movable terminal 63. The coupling 74 has a socket at its lower end for connection with the flexible conductor 24 which shunts the spring 9. Similarly, the flexible conductor 24 is connected to a socket at the lower spring head 50 75 to make connection to suitable stud 118, fitting in a socket in the cap member 3. At its upper end the movable terminal or plunger has an arcing tip 112 to which are connected both the high tensile strength strain wire 8 and the 60 silver fuse wire 7. At their upper ends the strain wire 8 and the fuse wire 7 are fastened to a removable arcing tip terminal member 113 which is formed in the shape of a headed screw threaded into and extending through a hollow tubular stem 65 member 114. The stem member 114 has a flange 115 with the periphery thereof tapered off to form a tapered valve seat like a poppet valve. Suitable relief openings 116 are formed through the valve, otherwise the valve tends to close off 70 the space above it from the space below it by contacting with a tapered metal seat 117 which is formed as an annular inwardly extending flange on a sleeve or ring member 118 that is threaded at its upper end into the main upper 75

ferrule 2. At its lower end the ring or sleeve 118 is internally threaded to receive the reduced and threaded end of a "Bakelite" fiber insulating sleeve 119. This insulating sleeve 119 fits loosely within the glass sleeve 1 and provides within its bore an arcing chamber which is substantially filled with the dielectric arc extinguishing liquid 20. The rodlike movable terminal 63 extends up through the bore of the tube 119 to a point adjacent the lower end of the hollow stem 114. The sleeve 119 at its lower end has a perforated plug 120 embracing fairly closely the lower end of the plunger terminal 63 and being provided with labyrinth grooves 122 to retard the flow of fluid through the space between the stem 63 and the opening in the plug 120. The perforated plug 120 is held in place at the lower end of the sleeve 119 by a ring 123 seated partially in a groove formed on the inside of the sleeve 119 and partially in the plug 120. A removable ring 124 on the upper end of the plug 120 provides a releasable shoulder for purposes of assembly. The plug is preferably made of insulating material. The upper ferrule 2, which forms the external terminal, is provided with an extending radial flange 125 with a cylindrical extension 126, which may be formed separately and screw threaded in place, or which may be formed integrally if desired. At its upper end the cylinder 126 is closed by a cap 127 threaded into the open end thereof and provided with a vent opening 128 closed by a releasable vent cap 129 cemented in place. A spider member 130 mounted in the upper end of the cylinder 126 immediately below the closure 127 has a central opening 132 through which is extended a threaded stud 133 and held in place by a clamping nut 134. The stud 133, at its lower end, has a clamping flange 135. The stud extends through the neck 136 of a closure member 137. This closure member is internally threaded to receive the upper end of a fiber cylinder 138 which forms the container for the automatic resistance unit 6b. The stud 133 thus clamps the closure member against the spider 130, holding the same in place.

The lower end of the fiber sleeve 138 is closed by a fiber disc 139 perforated at its center to receive the guiding sleeve 140. The guiding sleeve 140 has a flange 142 immediately above the fiber disc 139 and forced into engagement therewith by the hollow rod of insulation 143. This hollow rod of insulation 143 abuts at its upper end against the flange 135 of the stud member 133 and at its lower end against a flange 142 of the sleeve member 140. The hollow rod is plugged off at 144 by an integral wall which serves as insulation between the lower end of the stud member 133 and the upper end of the sleeve member 140. The flanges 135 and 142 form connections for the ends of the resistance wire 10, which resistance wire is made of tungsten or the like. The space between the sleeve 138 and the hollow rod 143 is filled with marble dust 12 to cooperate with the tungsten wire 10. The stud member 133 and the sleeve 140 are coupled together against rotary motion by pins 146-146. The hollow stem 114 within which the fuse and strain wire 7-8 are disposed, is guided within the sleeve member 140. The upper end of the terminal screw 113 is connected to the upper end of the metal sleeve 140 by a coiled flexible conductor 147 which, at its upper end, is connected by soldering to a spring clip forced into the upper end of the sleeve 140 and there soldered in place. The lower end of the flexible conductor 147 is soldered in

the socket formed in the upper end of the screw 113. The inside of the metal sleeve 126 which forms the outer chamber for the resistance unit 6b is lined with several layers of fiber paper 149. The metal parts of the outer sleeve or ferrule 2 and the internal ring 118 are covered by rings 150 and 152 formed of fiber or the like. The rings 150 and 152 are held together by press fit, and the threads on the ring 152 engage the internal threads of the metal ferrule 2, as shown in Figure 9, part 1. A series of annular cork washers 153 are disposed between the upper end of the resistance unit 6b and the inner wall of the chamber formed by the sleeve 126. These washers close off the annular space around the resistance element 6b and tend to limit the escape of liquid and gas to the upper metal cap member or closure 137.

The circuit made through the device is as follows:—From the lower terminal 3 through the stud 110, flexible conductor 24 to the movable plunger terminal 63 which is connected to the lower end of the fuse and strain wire 7 and 8. Thence the circuit proceeds through the fuse and strain wire to the upper terminal member 113, then the circuit divides, extending in one path down through the hollow stem member 114 which is made of metal, the flange 115, to the valve seat 117, ring member 118 and this, in turn, is in contact with the upper fuse ferrule 2; the other path, which is of higher resistance, extends through the flexible lead 147, sleeve 140, resistor 10, terminal 133, and through spider 130, sleeve 126, to ferrule 2.

Upon a rise in current which melts the fuse wire and strain wire 7 and 8 and releases the terminal 63, an arc is formed within the stem 114, but as this is of metal the arc will immediately tend to be shunted by the metal and extend only between the lower end of the stem member 114 and the arcing terminal 112.

The blowing of the fuse within the metal stem 114 provides a unique and useful action. As the fuse is vaporized the metal vapor is projected against the relatively cold walls and much of it is condensed and remains on the walls. It is therefore taken out of the arc because the metal stem affords a low resistance path which shunts the arc. The pressure which is generated by such blowing raises the valve, lengthening the gap between the lower end 111 and the arcing tip 112, thus taking a large part of the metal vapor out of the arc and almost instantly introducing a part or all of the gap which was removed by the arc being shorted by the tube. At the same time, the valve 115 leaving its seat tends to draw one or more arcs at this place, but the rush of vapor and liquid which bears against the bottom of the valve 115 tending to raise it, passes out the gap between the rim of the valve and the surrounding walls, particularly the flared wall of the insulating ring 152, tending to extinguish the arc or arcs from the rim of the valve 115 to the seat 117. The flared annular space between the valve 115 and ring 152 provides an expansion nozzle for the gases and vapors, tending to chill the valve 115 and also holding the main arc between tips 111 and 112 centralized. The liquid filling extends to approximately the lower end of the hollow valve stem 114 as indicated in Figure 9, where it is promptly acted upon by the pressure and heat of the arc to produce the action above described. The movable terminal 112 also begins to descend, adding its effect to those above described.

The result of the above action is to open the shunt originally existing about the resistance 10, causing said resistance to be in series with the main arc between the tips 111 and 112. The 5 circuit which contains the resistance 10 will immediately assume the burden of carrying the current, the arc or arcs between the flange or valve 115 and the seat 117 being extinguished and the current being all passed through the 10 tungsten wire 10. Immediately upon the current passing through the wire 10 it begins to heat up, and the automatic action of reducing its own conductivity by chemical reaction occurs. Meanwhile, the terminal member 63 is receding 15 under the action of the central spring 9, and while the above action may take place in so short a time as to permit the stem 63 to move downward only a short distance, its motion begins to be accelerated and by the time that the current 20 flow is interrupted, sufficient distance and sufficient dielectric liquid intervene to prevent re-striking of the arc, even though the valve member 115 with its hollow stem 114 drops downwardly. The shunt path containing the resistance 25 wire 10 is as follows:—From the hollow valve stem 114 through the flexible conductor 147 to the metal sleeve 140, through the flange 142 to the lower end of the wire resistance 10, then to the upper terminal of the wire 10 which 30 comprises the stud 133, through the spider 130, metal cylinder 126, to the flange 125 of the upper ferrule 2.

It is to be observed that the action of the valve in raising from its seat and interposing 35 resistance by the projection of fluid flow between the valve and its seat is designed to occur with great rapidity, since it is desirable to switch the resistance into the circuit and extinguish the connection between the valve 115 and the seat 40 117 in a fraction of a half-cycle.

The main arc between the arcing tip 112 and the lower end of the hollow stem 114 is not the one which is affected to effect the switching operation. It is the arc which tends to be drawn 45 between the members 115 and 117 as the valve and its hollow stem rise. Since arc extinguishing liquid is forced with considerable violence through the narrow space in which this arc must exist, the said arc, which is established only upon 50 said separating operation, has very little time to heat the adjacent parts or to establish a body of conducting vapor, with the result that it is quickly extinguished, although the main arc between the tip 112 and the lower end of the hollow stem 114 persists. The circuit is then subject to the two interrupting actions in series, 55 namely, that of the main arc and of the automatically increasing resistance. After the resistance has been switched in series with the arc 60 of the fuse, the operation is as described in connection with the previous embodiment.

The hollow valve stem may have a constricted outlet such as 121 through the side walls, preferably near the top, to permit some of the gas to escape and let the metal vapor occupy the space. In fact, the tube 114 may be extensively perforated so as to form chiefly a screen or basket, as shown in section in Figure 11, to catch the metal vapors and condense them. The arc within 65 the tube 114 is merely incidental to the use of a fusible link and the fusible link is a means for detecting excessive rise of current and for mechanically releasing the movable parts.

In the device of Figure 10 and as indicated in 70 75 the diagram of Figure 3, the resistance element

6c is in a shunt circuit and is switched in upon blowing of the fuse element 6c. It may be completely out of circuit, normally, and in that case a short arc or a movement of the terminal 155 may bring it into circuit.

In the device shown in Figure 10 the upper ferrule 2 has an extending flange 125 which, in conjunction with the metal sleeve 126 and the closure 127 forms a chamber at the upper end of the main glass sleeve 1. The lower end of the device shown in Figure 10 is substantially identical with the lower end of Figure 9, part 2, in that the spring 9 and the shunting flexible conductor 24 are connected to the lower ferrule 3 which closes the bottom of the glass sleeve 1. 15 The upper end of the spring is anchored through a suitable head 73 to a coupling 74 to which is connected a stud member 155 bearing a removable arcing tip 156. The strain wire 8 and fuse wire 7 are connected to the removable tip 156 as 20 heretofore described. The strain wire has a connection by way of a cross pin, giving a limited degree of universal motion and the coiled fuse wire 7, which is preferably made of silver, is laid in a slot extending endwise of the tip 156. At 25 the upper end of the wires 7 and 8 a similar connection is made to the terminal 157. The terminal 157, at its upper end, is connected to a number of parallel flexible strands 158 and they, in turn, are connected to a socket 159 of the terminal member which ends in the stud 160, clamped by means of a nut 162 to the spring spider 163. The spring spider 163 seats in a recess 30 in a perforated plate 164. The plate 164 is threaded internally in the brass sleeve 126, thereby making connection with the external terminal, 35 namely, the ferrule 2.

The resistance element 6c is housed within a sleeve of insulation 165 which, at its upper end, is closed by a head or plate member 166, having a 40 flange for piloting the sleeve and head together as shown at 167. The head 166 lies immediately below the plate or disc 164. The opposite end of the housing sleeve 165 is closed off by a similar head member 168 which has a piloting flange 169 45 for holding the "Bakelite" sleeve 165 in definite relation to the brass heads 166 and 168. A spacing sleeve of fiber 170 has an inwardly extending flange 172 threaded onto the upper end of a fiber liner 173, the lining sleeve being threaded into 50 the ferrule 2 and the lower end of the lining sleeve 173 extends down below the liquid level, as shown in Figure 10. A thin tubular metal sleeve 174 lies inside the upper part of the lining sleeve 173 and it is connected as by means of a 55 shoulder soldered to the lower head 168. At its lower end the metal sleeve or cylinder 174 has a relatively thick guiding flange 175 which fits relatively loosely around the stem 155 of the movable terminal. An insulating sleeve 176 lies within the 60 metal sleeve 174 and extends from the upper head 166 of the resistance unit 6c down to the flange 175 that is connected to the lower head 168 of said resistance unit 6c. A cylinder of porous insulating material surrounds the upper end of the 65 movable terminal 155—156, the fuse and strain wires 7 and 8, respectively, the upper terminal 157, flexible conductor 158, and communicates through a clamping ring 177 with the space above the disc 164. This aluminum oxide cylinder 178 70 is held in place by the threaded clamping ring 177 and forms, in effect, an arcing chamber. The cylinder of aluminum oxide is porous and the lower end thereof dips into the arc extinguishing liquid 20. It constitutes a wick for maintaining a 75

Supply of the dielectric arc extinguishing liquid throughout its length. The aluminum oxide cylinder 178 is preferably of such size as to fit relatively closely about the terminals and connections. It is of very high resistance to current flow and its function is to furnish both a refractory tubular wall and to serve as a wick for the liquid dielectric 20. The tungsten wire 10 is wound about the "Bakelite" sleeve 176, out of contact with the same, and the wire is surrounded by the filling 12 of marble dust or the like. The ends of the wire 10 are connected to the head members 166 and 168. The head member 168 is connected to the guiding flange 175 and the upper head member 166 is connected to the external terminal or ferrule 2.

Upon the occurrence of fault current the wires 1 and 8 become fused and an arc is established. Pressure is generated thereby within the aluminum oxide sleeve 178. The heat of the arc immediately evolves a gaseous medium from the liquid contained in the porous wicklike member 178 and such gaseous medium acts to expel the vapor of the fuse and the arc gases upwardly into the chamber 179 above the disc 164. At the same time the movable terminal begins to be retracted into the liquid. The upper terminal 157, its flexible leads 158 and the connecting spider 163 are expelled, thereby rapidly increasing the length of the arc and tending to extinguish the arc. As the resistance of the arc is thereby increased, sufficient potential difference between the ends of the arc will occur to cause the current to flow from the stem 155-156 to the metal guiding flange 175, which then switches the resistance 10 in parallel with the arc. The division of current, together with the extinguishing effect of the arc extinguishing medium, rapidly transfers the current flow to the resistance 10. Travel of the terminal 155-156 to a point below the guiding flange 175, if the arc has not previously been extinguished, will definitely extend the current flow through the resistance wire 10, and it thereupon automatically acts to efface itself as a conductor and to substitute a non-conducting oxide or other compound, terminating further current flow.

In this embodiment the resistance element 6c is sealed off completely from the liquid, although the liquid is carried to a level up to the top of the unit by the porous aluminum oxide cylinder 178.

After the current is switched to the resistance 10 its operation is as heretofore described.

The porous or absorbent cylinder 178 holds the liquid in definite position about the fuse, even though the actual level of the free liquid may be higher or lower. The free liquid level should be high enough to wet the lower end of the porous or wick-like member 178. This member need not be a complete tube to be effective. The preferred form is a self-sustaining refractory insulating member charged with arc extinguishing material which is evolved or released from the member by the arc, the medium being freely released, preferably through the body or structure of the member and not only from the surface. Other absorbent media may be employed, such as lava, asbestos, kieselguhr and the like.

In each of the above forms the releasable vent cap may be blown off if excessive pressure should be generated within the device. It is present as a safety feature not required on normal operation. The device may be recharged after each

operation in order to be assured of proper assembly and to secure freedom from impurities. After the device has operated to interrupt current flow, it is to be removed from the circuit. Its operation may readily be determined by inspection, this being possible at a distance in view of the employment of the glass sleeve, and the clear arc extinguishing liquid which is preferably employed. In each case, after the operation of the device, the fuse terminals are separated so as to disconnect the circuit and to provide a space which is then filled by a liquid dielectric of a high order.

It will be seen that the silver fuse wire is designed to act qualitatively, that is, to blow and form an arc when a definite current is reached or exceeded, whereas the tungsten wire is intended to act quantitatively, that is, to begin to reduce its conductivity when a definite current flow is reached or exceeded. When the silver fuse wire blows it forms an arc. When the tungsten wire reaches the temperature at which it begins to combine chemically with the reagent, for example, oxygen, it begins rapidly to increase its resistance. The above decrease of conductivity is quite aside from the change of resistance due to the temperature coefficient of the metal.

It is to be understood that I do not intend to be limited to silver wire and tungsten wire, respectively. Any metals which have substantially the capabilities required to perform the services of these two wires I consider to be equivalent. Certain alloys of copper, which have a high resistance to corrosion and good conductivity, may be employed instead of silver, or other metals or alloys of which I am not now informed may be substituted to perform the service of the silver fuse wire. Likewise, certain other metals such as tantalum, osmium, and perhaps others, may be employed in the place of the tungsten wire. Instead of the combination of oxygen with the metal of the resistance wire, some other reagent or active negative element or radical may be employed.

It is to be noted that the oxidation of the tungsten wire, or its equivalent, accelerates the heating. It is always desirable to have the tungsten or equivalent wire in relatively small strands in order to secure a relatively large ratio of surface to cross-section, to accelerate the action.

In the graph of Figure 5 I have shown the fault as occurring at the instant that the voltage crosses zero, so as to secure conditions which would lead to the greatest rate of current increase. This is the condition of greatest severity, and if the device can take care of such conditions it is fully capable of taking care of less severe conditions.

In connection with the fuse 5, it is not absolutely essential that the arc extinguishing liquid be employed in every case, but it is highly desirable to employ the same as a liquid dielectric between the terminals which open the circuit.

The fuse element measures the overload and initiates the circuit interrupting action. After the fuse has once melted the circuit is interrupted, whether the current rises further or not. If the current flow increases upon the establishment of the arc at a rate which indicates a high peak value, then the automatic resistance begins choking the current flow in proportion to the rate of increase. The rate of increase of current flow from zero towards maximum is indicative of the seriousness of the fault, other things being the same.

- I am aware that so-called "chemical fuses" have heretofore been proposed for use in low tension circuits. Examples of such fuses are disclosed in Hadaway Patent No. 620,309, and Sachs Patent No. 522,232. These fuses are intended to interrupt circuit flow without an arc by chemical action between the metal of the fuse and a co-operating compound, which action is initiated by the attainment of a certain temperature.
- 10 In actual practice, the action of such fuse is not all that may be desired for either low tension or high tension use, because of two defects which my present invention cures.
- First, such "chemical fuses" when subjected to 15 marginal operation will deteriorate, because a partial action may be initiated and not completed. Or, if the fuse stands for a time just below the point where active chemical action is to be initiated, the fuse likewise deteriorates. In either 20 case, the fuse rating is changed and the fuse thereafter will not carry full power load, and is quite unreliable.
- Second, such "chemical fuses" frequently, and especially on marginal operation, or by slow deterioration, will not convert the metal to complete non-conductivity. The fuse then will prevent any substantial flow of current because of the high resistance of the body thereof, but no actual gap is produced, and the fuse will still 25 transmit potential. This is of no great consequence where only low potential is involved, but upon high potential circuits, or where high potential is impressed upon the fuse, such transmission of potential is highly undesirable, and is 30 dangerous. Such partial conductivity may also result from the action resulting from a short circuit. The heat evolved may be great enough to melt the resulting compound, and thus produce a path of partial conductivity through the 35 melted residue.
- My invention overcomes both of the above defects, and provides a fuse suitable for any potential and particularly useful for high potential currents where the requirements are most severe. The manner in which this is done is fully 40 described above, but may be recapitulated in part as follows:
- The fusible conductor 5 (or 5b, 5c) which is the current measuring element is designed to 45 and will melt at a current flow through the device well below that at which any marginal operation of the "chemical fuse" 6 (or 6b, 6c) can be initiated. Hence, deterioration of the "chemical fuse" does not occur.
- 50 Next, the melting of fusible conductor 5 (or 5b, 5c) produces a gap in the metallic circuit whereby, if and when the "chemical fuse" operates and the current flow is interrupted by its action, the "chemical fuse" is completely disconnected, so that potential leakage through said 55 "chemical fuse" is rendered harmless. Whether the current flow is great enough to operate the "chemical fuse" or not, the melting of the fusible conductor fuse causes a gap and resultant 60 disconnection.
- By the above unique cooperation of a fusible conductor operating at a suitable low value of current flow as compared with the value of current flow required to initiate operation of the 65 "chemical fuse", a wholly new utility or combination is provided, not only in the production of a reliable efficacious fuse, but, in addition, a selective operation is produced in that for overload currents the fusible conductor may act alone to 70 interrupt current flow and produce a disconnect-

ing gap in the circuit without affecting the chemical fuse at all.

Upon short circuit currents, both fuses operate to extinguish a flow of current which may be so large that the fusible conductor fuse may be 5 incapable of interrupting it without the aid of the chemical fuse; and the fusible conductor fuse then disconnects the circuit to prevent potential leakage which the "chemical fuse" may not be able to do.

Thus the fusible conductor fuse protects the "chemical fuse" from deterioration and disconnects it if it operates, while the "chemical fuse" on the other hand reduces the heavy load on the fusible conductor fuse and permits it to perform its interrupting and disconnecting function, and the two fuses in addition act selectively.

I do not intend to be limited to the details shown and described.

I claim:

1. A protective device comprising a fuse element having automatically separable terminals, said fuse element having a link adapted to fuse and form an arc and permit said terminals to separate upon the occurrence of overload and a 25 resistance element having a stationary resistor permanently increasing its resistance upon the occurrence of a predetermined current flow therethrough and adapted to be connected in series with the arc to control the energy release 30 in the arc.

2. A protective device comprising a fuse element and a resistance element connected in series, said resistance element having means to cause it to increase its resistance permanently 35 substantially without arcing upon the occurrence of a current of predetermined value through the device, said fuse element being designed to blow at a value of current substantially lower than said predetermined value.

3. A protective device comprising a fuse element and a stationary resistance element connected in series, said resistance element having means to cause it to increase its resistance permanently upon the occurrence of a current of 45 predetermined value through the device, said fuse element having a fuse link provided with separable terminals and means to separate the fuse terminals upon the blowing of the link to interpose a definite gap in the circuit, the fuse 50 link being designed to blow at a value of current flow which will not cause the resistance to be permanently changed.

4. A protective device comprising a fuse element having a fusible link, a self-increasing resistance element having a resistor associated with the link, and means for automatically transferring current flow from the fuse element to the resistance element upon blowing of the link, said means introducing a permanent gap in series 60 with the resistance element.

5. A protective device for an electric circuit, comprising a fuse element having a fusible link, movable terminal means, a self-increasing resistance element having a resistor which acts by excessive current flow to increase its resistance permanently, said movable terminal means switching said resistance element serially into the circuit upon the blowing of the fusible link.

6. In a protective device, a fuse, and a refractory current limiting resistance comprising a conductor and a normally inert reagent, said conductor being of low ohmic value which upon a rapid increase of current flow through the fuse 70 75

- permanently increases its resistance to a high value without the formation of an arc.
7. In a protective device, a fuse, and a refractory current limiting resistance comprising a conductor and a normally inert reagent, said conductor being of low ohmic value which upon a rapid increase of current flow through the fuse permanently increases its resistance to a high value without the formation of an arc, and a single tubular fuse housing having external terminals for enclosing said fuse and current limiting resistance.
8. In a fuse, a fusible link and a surrounding sleeve comprising an absorbent insulating material wet with a liquid arc extinguishing material said sleeve comprising a porous granular refractory body.
9. In a fuse device, a fusible link, a surrounding sleeve of porous refractory insulation wet with a liquid arc extinguishing liquid and a sleeve of fibrous insulation capable of withstanding high internal pressures embracing said porous sleeve.
10. In a fuse device, a fusible link and a surrounding sleeve of aluminum oxide wet with arc extinguishing liquid.
11. In a fuse device, a fusible link, terminals for the link, means for moving one of said terminals away from the other upon blowing of the link, a body of liquid into which said movable terminal is moved, and a wicklike member extending alongside the fuse, a part of said member extending into the body of liquid and absorbing liquid therefrom.
12. In a fuse device, a fusible link, terminals for the link, means for moving one of said terminals away from the other upon blowing of the link, a body of liquid into which said movable terminal is moved, and a wicklike sleeve embracing a part of the link and the movable terminal and having a portion thereof in contact with the liquid.
13. In a device of the class described, a sleeve of insulation having external terminals at its ends, a fusible link in said sleeve connected at one end to one of said terminals, a limiting resistance within said sleeve, said resistance having terminals one of which is connected to the other external terminal, a spring within the sleeve anchored to the other end of the link and to the other end of the resistance and means within the sleeve for fixedly supporting said other end of the resistance and forming an anchorage for the adjacent end of the spring.
14. In combination, a fuse element, an oxidizable resistance element of relatively low initial resistance, means for connecting said elements in an electric circuit, means for permanently increasing the resistance upon predetermined temperature rise by flow of current therethrough, the fuse element being melted upon increase of current flow to a predetermined value, said value being less than the value of current flow at which said resistance element permanently changes its value, and means to conduct through the resistance element the flow of current through the arc which occurs upon blowing of the fuse and means for shielding the resistance element from the arc occurring upon the blowing of the fuse.
15. In combination, a fuse element, an oxidizable resistance element of relatively low initial resistance, means for connecting said elements in an electric circuit, means for permanently increasing the resistance upon predetermined tem-

perature rise by flow of current therethrough, the fuse element being melted upon increase of current flow to a predetermined value, said value being less than the value of current flow at which said resistance element permanently changes its value, means to conduct through the resistance element the flow of current through the arc which occurs upon blowing of the fuse, said means acting upon blowing of the fuse to switch the current flow of the arc through said resistance element.

16. In combination, a fusible conductor and a substantially infusible conductor connected in a parallel branch, terminals for said conductors, a compound in thermal contact with the infusible conductor, said compound being adapted to be heated by said second conductor to evolve a reagent which combines with said second conductor to render it less conductive, and spring means for increasing the resistance of the circuit including the arc formed upon fusion of said first conductor to cause the current to pass to said parallel branch.

17. In a device of the class described, the combination of a fuse melting at a predetermined current value, and a resistance melting at a relatively higher current value, said fuse having means to extinguish the arc caused by blowing of the fuse, and said resistance having means to render it substantially non-conductive without arcing upon rise in current flow to said relatively higher value, said fuse and resistance cooperating to reduce the current flow through the device and means to shield the resistance from the influence of the arc.

18. In a device of the class described, the combination of a pair of conductors adapted for connection in a circuit, the first conductor melting at a predetermined value of current flow, and the second conductor melting at a relatively higher value of current, upon increase in current flow the first conductor melting and forming an arc, means to separate the terminals of the arc independently of the second conductor, means to deionize the arc and interpose a dielectric between the terminals thereof, and means in thermal contact with the second conductor adapted upon being heated by said conductor by said relatively higher value of current to release a reagent which combines with the metal of the conductor, and reduces the same to a non-conductor.

19. In a device of the class described, a sleeve of glass having external circuit terminals upon the ends thereof, a conductor disposed within said sleeve, said conductor upon excessive flow of current therethrough being reduced by chemical action to a non-conductor, a fusible conductor disposed within the sleeve, said latter conductor having terminals, one of which is movable upon the melting of said fusible conductor, a liquid dielectric medium within said sleeve which is introduced into the space between said terminals upon the movement of said movable terminal, and means connecting said conductors to each other and to said external terminals.

20. In combination in an electric circuit, a pair of conductors, terminals for said conductors, one of said conductors having spring means for producing separation of its terminals only, and a normally inert chemical reagent activated by heating of the other conductor to combine with the material thereof to produce a substantially non-conducting compound, said other conductor being heated to the degree required to activate

said reagent only after said one conductor is fused.

5 21. In an electric circuit, a tungsten wire and a silver wire connected in parallel branches, a mass of limestone in contact with the tungsten wire, and a spring for extending the arc caused upon fusion of the silver wire, and means for shifting current flow from the arc to the tungsten wire.

10 22. In an electric circuit, a tungsten wire and a silver wire connected in parallel branches, a mass of limestone in contact with the tungsten wire, a spring for extending the arc caused upon fusion of the silver wire, means for shifting current flow from the arc to the tungsten wire, and a body of dielectric liquid adapted to be interposed between the terminals of the fused wire upon cessation of the current flow.

15 23. In an electric circuit, a circuit protective device comprising a fuse which blows upon a predetermined rise of current through the device, a conductor which permanently changes its resistance only upon a higher rise of current than said predetermined rise, blowing of said fuse resulting in an arc, means to separate the terminals of the arc, an arc extinguishing medium for said arc, and means for conducting the current flow through said conductor upon blowing of the fuse.

20 24. The method of controlling the energy release in an arc, which comprises conducting the flow of current which sustains the arc through a refractory conductor, heating said conductor by such current flow to a temperature at which the substance of the conductor is active chemically, evolving by said heat a chemical reagent, combining said reagent with said conductor to reduce it to a substantially non-conductive state, and simultaneously extending the length of the arc.

25 25. In a device of the class described, a fuse housing, comprising a tubular sleeve having external circuit terminals forming closures for the sleeve, a resistance chamber in said housing but out of communication therewith, a refractory resistance conductor in said chamber, a compound in said chamber adapted to release a reagent for combining with the conductor, a fusible link in said housing, a movable fuse terminal, a spring for moving said fuse terminal, and a body of arc extinguishing material in the housing, said resistance conductor being included in series with the arc formed upon blowing of the fuse for controlling the energy released in the arc.

30 26. In a device of the class described, a fuse housing, comprising a tubular sleeve having external circuit terminals forming closures for the sleeve, a resistance chamber in said housing, a refractory resistance conductor in said chamber, a compound in said chamber adapted to release a reagent for combining with the conductor, an arcing chamber, a fuse in said arcing chamber, a movable terminal for one end of the fuse, a spring for moving said movable terminal independently of said resistance conductor, and a body of arc extinguishing liquid in said housing for acting upon the arc in said arcing chamber when the fuse blows, said refractory resistance controlling the energy released in said arc.

35 27. In a device of the class described, a fuse housing comprising a tubular sleeve having external circuit terminals forming closures for the sleeve, a resistance chamber in said housing, a refractory resistance conductor in said chamber,

a compound in said chamber adapted to release a reagent for combining with the conductor, an arcing chamber having a movable closure member at one end forming a fuse terminal, a rod-like fuse terminal projecting into the arcing chamber from the other end, an arc extinguishing medium for acting upon the arc formed upon blowing of the fuse, and a fuse between said terminals.

40 28. In a device of the class described, a fuse housing comprising a tubular sleeve having external circuit terminals forming closures for the sleeve, a resistance chamber in said housing, a refractory resistance conductor in said chamber, a compound in said chamber adapted to release a reagent for combining with the conductor, an arcing chamber having a movable closure member at one end forming a fuse terminal, a rodlike fuse terminal projecting into the arcing chamber from the other end, an arc extinguishing medium for acting upon the arc formed upon blowing of the fuse, and a fuse between said terminals, said movable closure member having a central arcing tip for controlling the position of the arc, said movable closure member controlling the current flow through said resistance.

45 29. In a device of the class described, a fuse housing comprising a tubular sleeve having external circuit terminals forming closures for the sleeve, a resistance chamber in said housing, a stationary refractory resistance conductor in said chamber, a compound in said chamber adapted to release a reagent for combining with the conductor to cause a permanent increase in the resistance of the conductor, a fuse in another part of said housing, a movable terminal for the fuse, an arc extinguishing medium for quenching the arc, a spring for said movable terminal, and a vent from said resistance chamber to atmosphere independently of said fuse containing part of the housing.

50 30. In a device of the class described, a fuse housing comprising a tubular sleeve having external circuit terminals forming closures for the sleeve, a resistance chamber in said housing, a refractory resistance conductor in said chamber, a compound in said chamber adapted to release a reagent for combining with the conductor, a fuse in another part of said housing, a movable terminal for the fuse, an arc extinguishing medium for quenching the arc, a spring for said movable terminal, and a vent from said resistance chamber to atmosphere independently of said fuse containing part of the housing, and a releasable vent for the part of the housing containing the fuse.

55 31. In a device of the class described, a housing, external terminals on said housing, a liquid quenched fuse in one part of the housing, an oxidizable resistance in another part of the housing, connections for said fuse and said resistance to said external terminals, and independent vents from said housing to atmosphere for said fuse and for said resistance.

60 32. In combination, a main tubular housing having external circuit terminals, a fuse at one end of the housing connected to one of said terminals, a movable terminal connected to the other end of the fuse, a spring in the housing connected at one end to said movable terminal, a resistance unit comprising a separate tubular housing within the other end of said main housing, external terminals on said separate housing, an automatic resistance member within said separate housing, a charge of suitable compound within said latter housing for combining with said

resistance, said spring being anchored at its other end to one of the terminals of the resistance unit, the other end of the resistance unit being anchored to the adjacent main housing terminal, 5 said fuse being adapted to melt immediately upon the attainment of a predetermined value of current flow, said resistance member being adapted to react with said compound only after said fuse is melted.

16 33. In combination, a main tubular housing having external circuit terminals, a fuse at one end of the housing connected to one of said terminals, a movable terminal connected to the other end of the fuse, a spring in the housing connected at one end to said movable terminal, a 10 resistance unit comprising a separate tubular housing within the other end of said main housing, external terminals on said separate housing, an automatic resistance member within said separate housing, a charge of suitable compound within said latter housing for combining with said resistance, said spring being anchored at its other end to one of the terminals of the resistance unit, the other end of the resistance unit being anchored to the adjacent main housing terminal, a tubular arcing chamber for said fuse, and arc extinguishing material for said fuse, said fuse being adapted to melt immediately upon the attainment of a predetermined value of current flow, 15 said resistance member being adapted to react with said compound only after said fuse is melted.

34. In a device of the class described, a sleeve of insulation, ferrules on the ends of the sleeve forming external circuit terminals, one of said ferrules having a tubular extension, an annular resistance unit disposed in said extension, said unit comprising a resistor, a fuse substantially in axial alignment with said unit, a spring disposed in said sleeve, a movable fuse terminal connected to said spring, a second fuse terminal connected to one end of said resistor and to the adjacent ferrule.

35. In a device of the class described, a sleeve of insulation, ferrules on the ends of the sleeve forming external circuit terminals, one of said ferrules having a tubular extension, an annular resistance unit disposed in said extension, said unit comprising a resistor, a fuse substantially in axial alignment with said unit, a spring disposed in said sleeve, a movable fuse terminal connected to said spring, and a second fuse terminal connected to one end of said resistor and to the adjacent ferrule, said unit having a central opening within which a portion of said second fuse terminal is disposed, said terminal being movable in said opening under the fluid pressure occasioned by blowing of the fuse.

36. In a device of the class described, a sleeve of insulation, ferrules on the ends of the sleeve forming external circuit terminals, one of said ferrules having a tubular extension, an annular resistance unit disposed in said extension, said unit comprising a resistor, a fuse substantially in axial alignment with said unit, a spring disposed in said sleeve, a movable fuse terminal connected to said spring, and a second fuse terminal connected to one end of said resistor, and to the adjacent ferrule, said unit having a central opening within which a portion of said second fuse terminal is disposed, said terminal being movable in said opening under the fluid pressure occasioned by blowing of the fuse, said last named terminal serving to switch all the current through the 75 resistor.

37. The method of permanently interrupting current flow in a circuit, which consists in vaporizing one portion of the circuit, oxidizing another portion of the circuit to interrupt current flow and replacing a third portion of the circuit by a dielectric to prevent reestablishment of current flow. 5

38. The method of permanently interrupting current flow through a circuit, which consists in vaporizing one portion of the circuit to form an arc, oxidizing another portion of the circuit to 10 reduce the current flow through the arc, so that it can be easily extinguished, and replacing a third portion of the circuit with a dielectric to prevent reestablishment of current flow through the circuit. 15

39. The method of permanently interrupting current flow through a branched circuit, which consists in vaporizing a portion of one branch to form an arc, shifting a portion of the current from this first branch to a second branch, so 20 that the arc is easily extinguished in the first branch, oxidizing a portion of the second branch into an insulating compound to interrupt current flow through it, and replacing an unbranched portion of the circuit by a dielectric to prevent 25 reestablishment of current flow.

40. The method of interrupting current flow through a circuit, which consists in vaporizing one portion of the circuit and forming an arc, and oxidizing another portion of the circuit to reduce 30 the current flow in the vaporized portion to a point where the arc will not sustain itself.

41. In combination, a fusible link, an arcing chamber in which a portion of the arc is formed on fusing of the link, an arc extinguishing material, and capillary means for bringing a portion of the arc extinguishing material and sustaining the same within the walls of the chamber. 35

42. In a liquid filled fuse, a fusible link maintained in a definite position, a liquid filling of arc extinguishing material, and means for maintaining the effective level of the arc extinguishing material relative to the link independently of temperature variations of the medium surrounding 45 the fuse.

43. The method of removing metallic vapor from an arc evolved upon blowing of a silver fuse, which comprises condensing the metallic vapors upon an enclosing metallic wall. 50

44. In a device of the class described, a fusible link, a stationary sleeve embodying an arc extinguishing material surrounding the link, said sleeve being porous to permit the evolution of a gaseous arc extinguishing medium from the body 55 of the sleeve under the heat of the arc and a stationary sleeve of insulation surrounding said first sleeve for directing said gaseous medium endwise of the arc formed upon blowing of the link.

45. In combination, a resistance which is self-increasing for currents above a predetermined value, a shunt about said resistance including a switch, a spring, and a fuse through which the spring holds the switch closed. 60

46. A protective device comprising, in combination, a fuse adapted to be melted and to form an arc, a resistance element which is self-increasing for currents above a predetermined value adapted to be connected in parallel with the arc when the fuse blows, a switch, and a spring released by 70 melting of the fuse for operating the switch to conduct the entire current flow through the resistance element.

47. A protective device comprising, in combination, a fuse and a resistor which is self-increasing 75

for currents above a predetermined value, a switch adapted to connect the fuse and resistor in parallel, and a spring for operating the switch, said spring being normally restrained by the fuse and being released by the blowing of the fuse.

48. A protective device comprising, in combination, a resistance element which is self-increasing above a predetermined value of current, a switch connected in series with said resistance element, a spring for operating said switch, and a fuse adapted to be connected in parallel with the resistance element through said switch, said fuse holding the switch against the tendency of the spring to operate it.

15 49. In combination, a fuse comprising a fusible link, a refractory metal resistor connected in series with said link, a charge of oxygen-containing material in contact with the resistor, the oxygen having an affinity for the refractory resistor when the latter is heated substantially to incandescence, the fusible link and resistor being so proportioned that upon an increase of current flow in a half-cycle the fuse will melt and form an arc before the refractory resistor does, said refractory resistor combining with the oxygen substantially at incandescence and rapidly increasing its resistance to a high value, thereby reducing the current flow through the arc.

30 50. In combination, a fuse comprising a fusible link, a refractory metal resistor connected in series with said link, a charge of oxygen-containing material in contact with the resistor, the oxygen having an affinity for the refractory resistor when the latter is heated substantially to incandescence, the fusible link and resistor being so proportioned that upon an increase of current flow in a half-cycle the fuse will melt and form an arc before the refractory resistor does, said refractory resistor combining with the oxygen substantially at incandescence and rapidly increasing its resistance to a high value, thereby reducing the current flow through the arc, means for deionizing the arc occurring at the fuse, and a body of insulating liquid interposed between said link and said resistor to segregate the link and resistor from each other's influence.

35 51. The method of interrupting within a half-cycle of alternating current the current flow through a conductor, which comprises fusing a portion of the conductor to form an arc, exerting a deionizing action upon the arc, simultaneously oxidizing another part of the circuit to increase the resistance, by said increase of resistance reducing the flow of current to a value 40 at which the deionizing action will extinguish the arc before the occurrence of the next half-cycle of current flow.

52. In a device of the class described, a fusible link, a body of arc extinguishing liquid, and a porous refractory sleeve surrounding the link and having a portion in contact with the liquid and serving to raise liquid by capillary action.

53. A protective device comprising a fuse element having terminals, a spring for separating said terminals upon melting of the element, arc extinguishing material adapted under the influence of the arc to form a gaseous arc extinguishing medium, means for guiding said medium lengthwise of the arc, and a resistance element which is self-increasing for currents above a predetermined value adapted to be connected in series with the arc caused upon blowing of the fuse, said resistance element being independent of the fuse element and its spring, the fuse element being designed to melt at a value of current

flow below that at which the resistance is self-increasing.

54. In combination, a fuse fusible within a half-cycle of alternating current, and a resistor provided with means rendering it capable of permanently increasing its resistance without arcing within the same half cycle upon the rise of current flow to a predetermined value above that at which the fuse melts, the resistor when it operates limiting the interrupting duty of the fuse, and the gap produced by the melting of the fuse disconnecting the circuit against leakage of potential through the resistor.

55. Method of interrupting current flow through a conductor upon the ends of which an increasing electromotive force is impressed tending to increase the current flow, which comprises fusing one portion of the conductor and forming an arc when the flow reaches a certain value and after said arc is formed and while said electromotive force is still increasing, reducing another portion of the conductor to a non-conducting compound, thereby increasing the resistance to said current flow so greatly that the current flow cannot maintain the arc.

56. In combination in a circuit, a blast quenched type of fuse adapted to blow at a first predetermined value of current flow, said fuse comprising a closed recombining chamber capable of remaining closed upon interruption of a flow of current below a second predetermined value, which second value is substantially greater than said first value, and a conductor mounted in fixed position and provided with a chemical compound adapted when heated by a suitable value of current flow through the conductor to react with the substance of the conductor to form substantially a non-conductor and thereby increase the resistance in the circuit, said reaction when initiated introducing sufficient resistance to keep the current in the circuit from rising above said second predetermined value.

57. In combination in a circuit, a fuse comprising a silver fuse link adapted to melt at a predetermined current flow and form an arc gap in the circuit, a tungsten wire and a charge of a limestone associated with the wire and adapted to react therewith when the wire reaches a predetermined temperature, said tungsten wire being heated to said predetermined temperature only after the fuse link is melted, and means for mechanically increasing the gap in the circuit when the fuse link melts.

58. In combination in a circuit, a fuse comprising a silver fuse link adapted to melt at a predetermined current flow and form an arc gap in the circuit, a tungsten wire and a charge of a limestone associated with the wire and adapted to react therewith when the wire reaches a predetermined temperature, said tungsten wire being heated to said predetermined temperature only after the fuse link is melted, means for mechanically increasing the gap in the circuit when the fuse link melts, and an arc extinguishing medium for deionizing the arc in said gap.

59. The method of interrupting current flow through a conductor upon the ends of which there is impressed an increasing electromotive force tending to cause the current to increase through the conductor, which comprises producing a gap in one part of the conductor when the current flow attains a predetermined value, the current forming an arc at said gap, increasing the length of said gap, and when the current flow attains a value substantially in excess of said predeter-

mined value chemically combining another part of the conductor with a reagent which reduces the conductivity of said other part.

60. In combination in a circuit, a pair of conductors, one of said conductors being vaporizable by current flow within the range of operation of the device, an arc extinguishing medium associated with said vaporizable conductor, and a chemical compound associated in fixed positional relation with the other conductor for reacting therewith only after said one conductor is vaporized.

61. In combination in a circuit, two fuses, one of which, when subjected to its rated current, blows and forms an arc, the other of which is normally ineffective and which changes into substantially a non-conductor without forming an arc only after the first fuse blows.

62. In combination in a circuit, two fuses, one of which, when subjected to its rated current, blows and forms an arc, the other of which is normally ineffective and which changes into substantially a non-conductor without forming an arc only after the first fuse blows, and means for invariably increasing the gap at the arc when said one fuse blows.

63. In combination in a circuit, two fuses, one of which, when subjected to its rated current, blows and forms an arc, the other of which is normally ineffective and which changes into substantially a non-conductor without forming an arc only after the first fuse blows, and means for invariably increasing the gap at said arc, and means for deionizing the arc when said one fuse blows.

64. In combination, a main tubular housing comprising metallic ferrules, a fuse in the housing, separable terminals for the fuse, spring means for separating the terminals when the fuse blows, a metallic sleeve concentric with but spaced radially from said housing and closely surrounding the fuse and being electrically connected to one of said terminals, said sleeve being adapted to condense metal vapor formed on blowing of the fuse.

65. In combination, a fuse, separable terminals for the fuse, at least one of said terminals being movable, a movable metallic sleeve closely surrounding and extending longitudinally of the fuse and serving to conduct away heat given off by the fuse and for condensing metallic vapors of the arc, said sleeve being substantially filled with gas, a spring for separating the terminals and a body of arc extinguishing material outside the sleeve for deionizing the arc.

66. In combination, a tubular housing, a silver fuse in the housing, terminals for the fuse, a metal tube closely surrounding the fuse and serving to condense upon its inner walls the silver vapor formed upon blowing of the fuse, a spring for moving one of the terminals away from the tube, the arc being extended in length by movement of said terminal and tending to persist between said movable terminal and said tube, and arc extinguishing material in the housing surrounding the movable terminal.

67. In combination, a silver fuse, terminals for the fuse, a metal tube surrounding the fuse and serving to condense upon its inner walls the silver vapor formed upon blowing of the fuse, a spring for moving one of the terminals away from the tube, the arc being extended in length by movement of said terminal and tending to persist between said movable terminal and said tube, a body of liquid into which said movable terminal is

drawn and a closed recombining chamber into which the remaining metallic vapor and the gaseous products of the action of the arc upon the liquid are driven.

68. In combination, a fuse, a stationary annular terminal, a movable metallic tube embracing the fuse having a flange resting on said terminal, a closed recombining chamber having its walls joined to said terminal to provide an annular space about said tube, a tubular housing extending from the other side of the annular terminal containing a charge of arc extinguishing material, a fuse in the tube, a spring retracted fuse terminal in the tubular housing, said tube comprising a condenser for the metal vapors of the fuse.

69. In combination, a fuse, a stationary annular terminal, a movable metallic tube embracing the fuse having a flange resting on said terminal, a closed recombining chamber having its walls joined to said terminal to provide an annular space about said tube, a tubular housing extending from the other side of the annular terminal containing a charge of arc extinguishing material, a fuse in the tube, a spring retracted fuse terminal in the tubular housing, said tube comprising a condenser for the metal vapors of the fuse, means for guiding said movable tube in alignment with the tubular housing, said tubular housing directing the products of the action of the arc upon the arc extinguishing material upon the end of said tube.

70. In a circuit interrupter, means for producing an arc at predetermined current value, separate current actuated means for arresting the growth of the arc and rapidly reducing current flow, and means producing separation of the terminals of the arc for extinguishing the arc and disconnecting said current actuated means.

71. In combination, in a circuit, a first fuse at which an arc is formed extended and extinguished, and a second fuse by which the current flow in the said arc is controlled and reduced through increase of resistance without formation of a second arc to assist the extinguishment of the arc at the first fuse, the gap produced by the first fuse disconnecting the second fuse to prevent leakage of potential through the circuit.

72. A self-contained high potential fuse device, comprising a tubular housing with fixed external terminals for connecting the device in an external circuit, said terminals being normally connected internally of the housing by conducting means, the conductivity of which is automatically destroyed upon the occurrence of excessive current flow, said conductive means comprising a first metallic conductor which melts at a certain temperature to form a gap, and a second metallic conductor having within its influence a chemical compound, said second conductor and said compound being correlated to produce a chemical reaction between them only when substantially a second certain temperature is reached, said reaction converting the metal of said second conductor to substantial non-conductivity, a current flow in excess of a predetermined value through said conductive means invariably raising the first conductor to its melting point and producing a gap, means associated with said first conductor for assisting in the extinguishment of any arc formed at the gap, the second conductor being raised only to a temperature below that at which said chemical reaction occurs by a current through the device great enough to melt said first conductor, whereby upon the occurrence of a current flow of a value corresponding substantially to an overload in the connected circuit the

first conductor forms a gap and the flow of current is interrupted thereat without action of the second conductor, and upon the occurrence of a current flow of a value corresponding substantially to short circuit conditions in the connected circuit the first conductor is melted to form a gap and the second conductor is heated to a temperature which initiates said chemical reaction and which reaction permanently increases the resistance of the second conductor to limit the value of current flow through the device.

73. In a fuse device for use in a high tension circuit, the combination of a conductor having associated therewith a compound which upon being heated to substantially a predetermined temperature initiates a chemical reaction with the conductor to render it substantially non-conductive, said conductor being heated to said reaction initiating temperature only upon the flow of current therethrough corresponding to a low impedance fault in the circuit, and automatic current controlled means associated with said conductor for forming a gap in series with said conductor upon the flow of current through said device as great as or greater than that corresponding to a high impedance fault in said circuit.

74. In a fuse device for use in a high tension circuit, the combination of a conductor having associated therewith a compound which upon the attainment of a predetermined temperature of the conductor by current flow therethrough reacts with the substance of the conductor to form a substantially non-conductive compound, automatic current controlled means associated with said conductor in said device for forming a gap upon the flow of current in excess of a predetermined value through said device, and means for lengthening said gap to a point where the arc will not restrike after extinguishment.

75. In a fuse device adapted to be connected in a high tension circuit, the combination of a main housing, a metallic conductor having associated therewith a cooperating compound which upon the attainment of a predetermined temperature of the conductor by current flow therethrough reacts with the metal of said conductor to form a substantially non-conductive compound, a second housing comprising tubular side walls of insulation and having metallic end pieces constituting external terminals disposed within said main housing, said conductor being disposed in said second housing and said cooperating compound being disposed in said second housing in contact with said conductor, a fusible link, arc extinguishing material for said link, and a spring for extending the gap formed by melting of the link, said link, material and the spring being disposed in the main housing outside the second housing.

76. In a fuse device adapted for connection in a high tension circuit, the combination of a blast type fuse having a fusible link, spring separable terminals and arc extinguishing material to produce a blast of arc extinguishing medium by the melting of the link and formation of an arc, and

a stationary non-arcing chemical fuse connected in series with the arc formed by the blast type fuse.

77. A fuse device for connection in a high tension circuit, a housing comprising a tubular sleeve of insulation having metallic end pieces for providing external terminals, means dividing said housing into two compartments, a fusible link in said one compartment, a refractory metal conductor in the other compartment, and a chemical compound adapted to react with the metal of the refractory conductor upon heating of the conductor by a predetermined current flow to convert it to substantially a non-conductor, and means within said housing for connecting said link and said conductor in series between said metallic end pieces.

78. In combination for use in a high tension alternating current circuit, a chemical compound and a cooperating chemically convertible conductor which upon being heated by a predetermined current flow is converted into substantially a non-conductor but which might have sufficient conductivity to transmit a dangerous potential, and a fusible conductor adapted to melt and interpose a gap in series with the first conductor, which gap upon the cessation of current flow disconnects the first conductor so that dangerous potentials are not transmitted.

79. In a fuse device for high tension circuits, a fusible link, a movable terminal for one end of the link, a spring for retracting the terminal, arc extinguishing material adapted to be acted upon by the arc to evolve a gaseous blast producing medium, a chemical fuse having terminals one of which is connected to an end of the fusible link and the other of which has sliding engagement with said movable fuse terminal.

80. The combination of claim 78 wherein the chemical fuse comprises a wire coiled loosely about the fusible link and has a chemical compound associated therewith, and said other terminal of the chemical fuse comprises an annular metal ring embracing the movable terminal of the fusible link.

81. In a high potential circuit, the method of stopping the flow of current through a conductor which comprises melting a first part of the conductor to form a gap in the conductor and converting by chemical action a second part of the conductor to substantially a non-conductor whereby the current flow is reduced to such a value that an arc at the gap will not sustain itself, the gap then serving to disconnect the circuit against leakage through the second part of the conductor.

82. In a high potential circuit, the method of stopping the flow of current which comprises forming a gap in the circuit, an arc being formed at said gap, then increasing the resistance of the circuit to a value high enough that the arc at said gap will not sustain or reestablish itself, said gap serving to prevent leakage of current through said increased resistance.

HUGH A. TRIPLETT.
